UNITED STATES PATENT OFFICE

1,975,427

AIR ACTIVATOR

Robert John, New York, N. Y.

Application August 29, 1932, Serial No. 630,970

12 Claims. (Cl. 204—32)

This invention relates to means for regulating the quantity and/or character of the output of oxygen activators or ozonizers and methods for utilizing such means to produce useful results.

5 The means and the methods herein are adaptable to many kinds of ozonizers and other oxygen activators but are particularly useful in conjunction with air activators of the type described in my co-pending application, Serial No. 623,227, filed July 18, 1932, in which is disclosed an air activating element in which the degree and/or character of activation is governed by the lateral spacing apart of an under and an outer electrode secured to opposite faces of a single dielectric 15 plate.

It is obviously advantageous to be able to vary the amount of output or its character, or both, of such an air activator, to suit different conditions, without changing the internal structure 20 of the air activating device. The present invention has for its object to provide an external means for effecting such changes whereby the output of a given air activator may be varied at will, by the turning of an external dial without 25 altering the internal structure of the device or effecting any permanent change therein or harm thereto.

It has been found that the output of devices 30 of the kind referred to above is influenced by the rise and fall of the line voltage of the power source to which the activator is connected; by differences in temperature and humidity; and by the specific requirements regarding the volume and character of output which arise from 35 time to time as a result of different uses to which the device may be put. It is a purpose of the present invention to provide a simple, inexpensive, and infallible means, whereby the volume and/or character of the activated gases produced 40 by such a device may be exactly suited to meet a wide range of differences in power input, a wide range of temperatures and humidity and a wide range of uses to which the instrument may be applied, all by the means of the manipulation of an external regulator.

Other objects and advantages will appear in the following description of one embodiment of the invention shown in the attached drawing, of which:

Figure 1 is an elevation partly in section of the air activator;

Figure 2 is a plan view showing the controlling means in intermediate position;

Figure 3 is a view similar to Figure 2 showing

the controlling means in one extreme position; and

Figure 4 is a view similar to Figure 2 showing the controlling means in its other extreme position.

Referring more particularly to the drawing, 10 indicates the air activating element in general, 11 a transformer casing upon which the element 10 is mounted, and 12 indicates the controlling means for the air activator.

The activator element 10 comprises a thin circular dielectric plate 13 mounted in a metallic rim 14. An electrode 15 which may be of metallic foil, is secured to the under surface of the dielectric plate 13 preferably by a thin layer of dielectric cement. As shown in Figure 1, the metal rim 14 completely surrounds the dielectric plate 13 and is provided with a notch 16 in which the dielectric plate is positioned. The metal rim 14 preferably extends downwardly from the dielectric plate to form an inverted dish-shaped element. The hollow portion of this dish-shaped element is preferably filled with a dielectric cement or other insulating material 17. A conductor 18 is in electrical connection with the electrode 15 and extends through the dielectric cement 17.

The upper wall 19 of the transformer casing 11 is provided with an aperture 20 in which is positioned a projection 21 on a dielectric member 22 suitably secured to the upper wall 19 as by rivets 23. Centrally located in the dielectric member 22, a metallic nut 24 is provided such that a portion 25 of the dielectric member 22 is positioned between the nut 24 and the exterior of the transformer casing. The connector 18 may be screw threaded as shown in Figure 1 to engage a screw threaded aperture in the nut 24, and serves to retain the air activator element 10 in position upon the transformer casing.

As shown in Figure 1, the outer surface of the metallic rim 14 is preferably flush with the outer surface of the dielectric plate 13 and this rim member is in electrical connection with the transformer casing and serves as one electrode 100 of the air activating element as will be herein-after described. The means 12 for controlling the character of the electrical discharge comprises a stud 26 suitably secured to the wall 19 of the transformer casing as by riveting over a portion 27 thereof which extends through an aperture 28 in the wall 19. The stud is provided with an upper screw threaded portion 29 of smaller diameter than the body of the stud providing a shoulder 30 which is in the plane of the outer 110

surface of the dielectric plate 13. A thin disc 31 of conducting material is provided with an eccentric aperture 32 which is positioned about the portion 29 of the stud 26 such that the disc 31 rests upon the shoulder 30. A nut 33 threaded upon the projection 29 of the stud serves to hold the disc 31 in adjusted position.

A transformer, not shown, is positioned within the transformer casing 11 and has one terminal 34 of its secondary connected to the nut 24 by wire 35. It will be noted that this terminal of the transformer is completely insulated from the transformer casing and the exterior of the device, even when the air activating element 10 is removed from the transformer casing. The stud 26 is grounded to the transformer casing 11 and serves as a convenient connection to the other terminal of the secondary of the transformer by means of the wire 35. The metallic rim 14 of the air activating element is also grounded to the transformer casing 11 and to insure good electrical connection a spring connector 36 may be positioned between the body portion of the stud 26 and the transformer casing so as to bear upon the rim 14.

As shown in Figures 2, 3 and 4, the eccentric disc 31 may be revolved about its pivot 29 and, because of its eccentricity about this pivot, may be adjusted to have any lateral spacing from the electrode 15 between the desired limits. In Figure 2 the edge of the disc is shown as being slightly spaced laterally from the electrode 15, in Figure 3 the disc is shown overlapping the electrode 15, and in Figure 4 the edge of the disc is shown entirely without the space between the electrode 15 and the electrode 14.

As an example of the specific construction of a device embodying my invention, the following description is given. The inner electrode 15 may be of tinfoil $1\frac{1}{4}$ inches in diameter and $5/1000$ of an inch in thickness. The dielectric plate 13 may be a circular piece of glass $1\frac{1}{2}$ inches in diameter and $18/1000$ of an inch in thickness, such that the metallic rim or outer electrode 14 is spaced laterally from the inner electrode by approximately $\frac{1}{4}$ inch. This construction is such that when a power input of 4800 volts, 60 cycle A. C. is used, the electrical input, the area of the inner electrode, the thickness of the dielectric plate, and the spacing apart of the electrodes are balanced so as to produce intense activation of the air when the disc 31 is in the position shown in Figure 4, without forming measurable quantities of ozone, said activation being completely free from the formation of oxides of nitrogen.

In a device as described above, a stud 26 is mounted so as to have its center $\frac{1}{4}$ of an inch distant from the periphery of the electrode 15. The disc 31 is of suitable metal such as spring brass, $5/1000$ of an inch in thickness, or any other electrically conductive metal, said disc being approximately $1\frac{1}{8}$ inches in diameter and having the center of its eccentric aperture 32 spaced $\frac{3}{4}$ of an inch from one edge of the periphery of the disc and $\frac{3}{8}$ of an inch from the opposite edge. As described above, the stud 26 along with the electrode 14 is connected to the ground potential side of the electrical power source, and the disc 31 is placed in such a position that it is held from lateral movement by the threaded portions of the stud and from vertical movement by the shoulder thereof and a threaded nut screwed down on the threaded portion of the stud.

I find now that if I loosen said nut and rotate

said disc on its eccentric axis to the position which permits of the greatest overlapping of the dielectric plate, that the disc is then superimposed by approximately $\frac{1}{8}$ of an inch over the under electrode of the activating element. If I then impress the aforesaid voltage from the under electrode to the newly formed ground electrode represented by the disc, the discharge is so intensified by reason of the disc that measurable quantities not only of ozone but of oxides of nitrogen are formed.

80

85

I find that if I next rotate my disc to a point where its periphery is approximately above the periphery of the inner electrode, there being no overlapping of electrodes, and similarly impress said voltage across said electrodes, that I form measurable quantities of ozone but no quantities whatever of the oxides of nitrogen.

90

If I still further rotate my disc to the position of a half turn from its original position, I find that its periphery is approximately directly over the circle formed by the inside of the fixed outer electrode, and that upon impressing said voltage across the electrodes, no ozone whatever is formed, but merely an activation of the air occurs, exactly the same as though the disc were not a part of the device.

95

As indicated at 37, the disc may be provided with graduations and a zero line 38 may be etched or otherwise formed upon the surface of the dielectric plate.

105

By practicing the foregoing procedures, I find that it is possible to vary the output of the activating element by infinitesimal degrees merely by turning the disc through the radius of a semi-circle. I also find that if greater percentages of the oxides of nitrogen are unobjectionable, a disc of larger diameter, and of greater eccentricity, may be employed to produce this result as well as all of the intermediate results; and that if it is deemed inadvisable under any conditions to produce the oxides of nitrogen, a smaller disc than that first described above and of less eccentricity, may be employed. That is, if the disc is of such a diameter and eccentricity that the overlapping of the electrode 15 and disc 31 can be increased, the percentage of oxides of nitrogen can be increased or if the diameter and eccentricity of the disc is such that it is impossible to overlap the disc 31 and the electrode 15, no oxides of nitrogen will be produced. I find also that the output may be increased both in character and intensity by positioning two or more discs similarly spaced around the outer rim of the activating element. I also find that when it is desired to produce relatively large quantities of the oxides of nitrogen, it is possible to accomplish this to a still further extent than above described, if the discs, instead of possessing a smooth circular periphery, are formed with pointed teeth, as those of a circular saw. I still further find that if instead of a solid, flat, metal disc, a similar disc of wire gauze or corrugated metal be employed, that the entrapping pockets therein provide a means for re-treatment of the ozonized gases and form still increasing amounts of the oxides of nitrogen.

150

The usefulness of the invention disclosed above will be obvious to those skilled in the art. As a single illustration it may be pointed out that ozonization is useful in household refrigerators, in deodorizing the mixed food smells of the food compartment and in preserving the food from harmful bactericidal action. It has been found, that if the degree of activation of air of the food compartment is insufficient, the odors are not sat- 150

isfactorily eliminated, while, on the other hand, if over-ozonization occurs the edible fats, as butter, etc., are partially converted into foul smelling, disagreeable tasting ozonides. It is well known

- 6 that the food compartments of such refrigerators vary in size, usually from 4 cubic feet to 20 cubic feet; that the power input is subject to great variation due to the locality in which the refrigerator is installed; and it has been found that changes
- 10 in temperature and humidity affect the quantity and character of the output of an air activator within the food compartment of such a refrigerator. By way of explanation of this latter statement, it may be pointed out that the temperature
- 15 and humidity of the food compartment of such a refrigerator when the door is closed is fairly constant; but when with an internal temperature of 40° F. with, say, 70% relative humidity, the door of the refrigerator is opened and air
- 20 of 80°, with 75% humidity, is admitted, a film of water instantly forms all over the interior of the food compartment and on the surfaces of the air activator itself. From the foregoing it will be seen that an air activator suitable under certain
- 25 conditions in a household refrigerator might be unsuitable under others. The present invention, however, makes it possible to employ the same device under all normal variations of electrical current, size of food compartment, and changes
- 30 of temperature and humidity, merely by rotating the dial or disc above described. Likewise, in all other situations in which air activators are useful, it will be found that the wide range of variations have heretofore made the employment of
- 35 a single instrument impossible, but that special activators have to be devised for special needs. The present invention provides a means whereby the exact degree of air activation within the range of possibilities of a given electrical input
- 40 may be accurately produced and may be varied from time to time to meet changing conditions.

In the foregoing embodiment of my invention reference is made, purely for the purpose of illustration, to its adaptation to the air activator of my co-pending application referred to. I desire it understood that my new activator and the method of using it is not limited to this use but that it may, without departing from the scope of the invention, be employed either with or without modification to the control of any other type of air activators and ozonizers. I further point out that whereas for the purpose of illustration I have described an embodiment of my invention which employs a rotatable disc, that I do not limit myself to this form of construction but have successfully used other types of movable ground potential terminals, such as flat strips which may be advanced or retracted laterally across the dielectric plate, and such as fine wires centrally

- 50 embedded in screws, which wires may be brought closer to or farther from the dielectric plate by the turning of their supporting screws, which screws may be mounted in threaded holes positioned to accomplish this result and suitably connected to the high tension voltage of the transformer so as to be at ground potential.

An important feature of my invention resides in the provision of an external, movable element by the mechanical manipulation of which either

- 70 the quantity or the character of the output of an air activator, or both, may be varied without altering the internal construction of the air activator and which, if desired, may be adjusted so as to not interfere with the normal output of
- 75 such activator.

I claim:

1. In an air activator, a dielectric plate, a first electrode secured to one face of said plate, a second electrode having a surface adjacent the other face of said plate and normally spaced laterally from said first electrode and means to vary the lateral spacing between said electrodes.

2. An air activator comprising a relatively thin dielectric plate, an electrode in contact with one face of the dielectric plate and a second electrode in contact with the other face of the dielectric plate, said electrodes being normally spaced laterally from each other, means to impress an electrical potential across said electrodes, at least one of said electrodes being exposed to the air being treated and at least one of said electrodes being movable in the plane of a face of the plate to vary the lateral spacing of said electrodes.

3. An air activator comprising a relatively thin dielectric plate, an electrode in contact with one face of the dielectric plate and a second electrode in contact with the other face of the dielectric plate, said electrodes being normally spaced laterally from each other, means to impress an electrical potential across said electrodes, at least one of said electrodes being exposed to the air being treated and at least one of said electrodes being movable in the plane of a face of the plate to vary the lateral spacing of said electrodes, and means to lock said electrode in adjusted position.

4. An air activator comprising a dielectric plate, an electrode secured to one face of the dielectric plate and spaced from the edges thereof, a second electrode surrounding said dielectric plate and having a surface substantially in the plane of a face of said dielectric plate, and means to impress an electric potential across said electrodes.

5. An air activator comprising a dielectric plate, an electrode secured to one face of said dielectric plate, said electrode being spaced from an edge of said plate, a second electrode engaging said edge of said plate and extending outwardly therefrom, said second electrode having a surface substantially in the plane of a face of said plate, and means to impress an electric potential across said electrodes.

6. An air activator comprising a dielectric plate, an electrode secured to one face of said dielectric plate, said electrode being spaced from an edge of said plate, a second electrode engaging said edge of said plate and extending outwardly therefrom, said second electrode forming a support for said plate and having a surface substantially in the plane of a face of said plate, and means to impress an electric potential across said electrodes.

7. An air activator comprising a relatively thin dielectric plate, an electrode in contact with one face of said plate, said electrode being spaced from an edge of said dielectric plate, a second electrode engaging said edge of said dielectric plate, said second electrode extending outwardly from said edge and having a surface substantially in the plane of the other face of said dielectric plate, an auxiliary electrode having a surface in the plane of said other face of said plate, said auxiliary electrode being movable over the surface of said other face of said plate.

8. An air activator comprising a relatively thin dielectric plate, an electrode in contact with one face of the dielectric plate and a second electrode in contact with the other face of the dielectric plate, said electrodes being normally spaced lat-

erally from each other, means to impress an electrical potential across said electrodes, at least one of said electrodes being exposed to the air being treated and at least one of said electrodes being movable in the plane of a face of the plate to vary the lateral spacing of said electrodes, said movable electrode comprising a conducting disc mounted upon an eccentric pivot.

9. An air activator element comprising a relatively thin dielectric plate, a thin metallic electrode secured to one face of said plate and spaced from the edges thereof, a metallic rim of conducting material surrounding said plate and engaging said edges, said rim forming a second electrode, and means for producing an electrical discharge between said electrodes.

10. An air activator element comprising a relatively thin dielectric plate, a thin metallic ele-

trode secured to one face of said plate and spaced from the edges thereof, a metallic rim of conducting material surrounding said plate and en-gaging said edges, said rim forming a second electrode, and means for producing an electrical discharge between said electrodes.

11. An air activator element comprising a relatively thin dielectric plate, a thin metallic ele-

trode secured to one face of said plate and spaced

from the edges thereof, a metallic rim of con-

ducting material surrounding said plate and en-

gaging said edges, said rim having a surface ad-

jacent the edges of the plate, substantially in the

plane of the other face of said plate, said rim

forming a second electrode, and means for pro-

ducing an electrical discharge between said elec-trodes.

11. An air activator element comprising a relatively thin dielectric plate, a thin metallic ele-trode secured to one face of said plate and spaced from the edges thereof, a metallic rim of con-ducting material surrounding said plate and en-gaging said edges, said metallic electrode and the face of said plate to which said first electrode is secured being covered with a dielectric material, said rim forming a second electrode, and means for producing an electrical discharge between said electrodes.

12. In an air activator element, a first mem-ber comprising a relatively thin dielectric plate, a second member comprising a rim of conducting material surrounding said plate and engaging the edges thereof, said rim forming an electrode, one of said members being shaped to provide an open recess adjacent one face of said dielectric plate, an electrode having a surface adjacent the face of said plate within said recess, said electrode being spaced from said rim, said recess being filled with dielectric material.
